US0D1035358S

(12) **United States Design Patent** (10) **Patent No.:** **US D1,035,358 S**
(45) **Date of Patent:** **** Jul. 16, 2024**

(54) **CUP**

(71) **Applicant:** **Ember Technologies, Inc.**, Westlake Village, CA (US)

(72) **Inventors:** **Clayton Alexander**, Westlake Village, CA (US); **Daren John Leith**, Agoura Hills, CA (US); **Mikko Juhani Timperi**, San Marcos, CA (US); **Fenton Lane Stith**, Westlake Village, CA (US); **Jacob William Emmert**, Westchester, CA (US); **Rahul Mulinti**, Westlake Village, CA (US); **Edward Sebert Maurice Shelton**, Tetbury (GB); **Lolan Naicker**, Wiltshire (GB); **Simon David James**, Simi Valley, CA (US)

(73) **Assignee:** **Ember Technologies, Inc.**, Westlake Village, CA (US)

(**) **Term:** **15 Years**

(21) **Appl. No.:** **29/866,576**

(22) **Filed:** **Sep. 19, 2022**

(51) **LOC (14) Cl.** **09-01**

(52) **U.S. Cl.**

USPC **D7/305**

Primary Examiner — Joseph Kukella

Assistant Examiner — Darryl J Dardenne

(74) **Attorney, Agent, or Firm:** Knobbe, Martens, Olson & Bear LLP

(57) **CLAIM**

The ornamental design for a cup, as shown and described.

DESCRIPTION

FIG. 1 is a top perspective view of a cup embodying my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and

FIG. 8 is a bottom view thereof; and,

FIG. 9 is an exploded top perspective view thereof.

1 Claim, 9 Drawing Sheets
